UNITED STATES PATENT OFFICE.

WILLARD M. HARRIS, OF WYOMING, DELAWARE.

CULTIVATOR.

SPECIFICATION forming part of Letters Patent No. 29,017, dated February 5, 1884.

Application filed November 17, 1883. (No model.)

To all whom it may concern:

Be it known that I, WILLARD M. HARRIS, a citizen of the United States, residing at Wyoming, in the county of Kent and State of Delaware, have invented certain new and useful Improvements in Cultivators, of which the following is a specification, reference being had therein to the accompanying drawings, in which—

10. Figure 1 is a plan, Fig. 2 a side elevation, Fig. 3 a central longitudinal vertical section, and Figs. 4 and 5 details, of a cultivator constructed in accordance with my invention.

Like letters refer to like parts in all the figures.

15. My invention relates to that class of cultivators which are mounted on wheels and are intended to straddle the rows and operate upon the soil between and alongside the rows; and one of the objects of my invention is to arrange the teeth or shovels of the cultivator in pairs, and to connect each pair with the frame-work in such a manner that each pair will be adjustably held independently of the others, and so that the central pair may be 20 under the entire control of the operator, in order that said pair, which straddles the row, may be swayed sidewise to conform with any irregularities in the row.

25. Other objects and advantages will appear in the following description, and the novel features of my invention will be specifically set forth in the claims.

30. Referring to the drawings, A represents the wheels, which are mounted each upon a short axle, *a*, which is bent upwardly and laterally to form the usual arch. The central part of the arch is removed, and upon each remaining portion is secured one end of a side bar, *B*, 35 of the frame, the opposite ends of said side bars being secured to a front cross-bar, *B'*, and back of the latter is a rear cross-bar, *B''*. The pole *C* of the machine is composed of two strips, *c c*, the front ends of which are secured 40 to each other by bolts, rivets, ferrules, or any other suitable means, and in this instance so as to embrace and hold a neck-yoke hook, *c'*, while the rear ends of the pole-strips are each secured to the inner end of one of the arched 45 axles, and said strips are also secured to one or more of the cross-bars *B' B''*. It will thus be

seen that the main frame consists of the side and cross bars and the pole-strips, thus rendering the same not only simple, but strong and serviceable, and at the same time giving 55 it such a shape as to readily adapt it for the connection and operation of the elements hereinafter described. If desired, an additional cross-bar, *c''*, may be employed to stiffen the pole. Clips *B* serve to bind the seat-rails *B'* 60 to the side bars, while said rails are supported upon the cross-bars, thus giving a spring-support to the seat *B''*.

65. *D* represents the evener, and from each of its outer ends is suspended a whiffletree-strap, *D'*, the lower end of which is connected to the axle by a link or chain, *D''*. The strap *D'* is provided with a vertical series of holes for the purpose of connecting the whiffletrees at different elevations, as desired, whereby the draft 70 of the machine may be reduced to the minimum and adapted to different teams.

75. The cultivator-shovels are, as before stated, arranged in pairs, each pair constituting what I hereinafter designate as a "brake," there being a central brake, *E*, and two side brakes, *F*. All the brakes are of similar construction, and a description of one is sufficient. Each shovel of each pair is secured to the usual 80 clevis, *G*, retained pivotally on a curved beam, *H*, by a bolt or pin, *h*, and held in operative position by the usual wooden pin, *g*. Each shovel is secured to a suitable casting, *I'*, which is socketed to receive the ends of the beam *H*, which is cylindrical and shouldered, as shown 85 in Fig. 4, so that by use of a binding-screw, *i*, each shovel may be properly adjusted laterally with relation to the path of the machine.

90. Three depending rods or brackets, *J*, are provided, one located beneath and serving as the pivot-bolt of the evener and passing through the front cross-bar, *B'*, and one on each side of the machine and passing through and secured to the rear cross-bar, *B''*. In this instance each of the rods *J* is bent and extended to a 95 cross-bar in front of that through which it passes, for the purpose of giving additional strength to the rods *J*, and to the parts thus joined; but I do not limit myself to this exact feature of construction.

100. Upon the upright portion of the rods *J*, I mount a sliding clevis-block, *K*, having a bind-

ing or set screw, *k*, whereby it may be secured at different elevations to modify the dip of the shovels and the draft of the machine. Each of the beams *H* is secured to vertical 5 pivots *h* in a link, *L*, which is connected to the clevis-block *K* by a horizontal pivot or bolt, *l*, so that vertical and horizontal movements may take place in the shovels while the machine is in operation. The beams *H* of 10 each brake are united by a band, bar, or strap, *M*, having an eye or loop, *m*, to which a chain, *N*, is attached, the opposite end of which is secured to a shaft or roll, *O*, provided with an operating-lever, *P*, whereby the chains may 15 be wound up to shorten and unwind to lengthen them. In order to raise or depress the brakes, as usual, a catch, *p*, serves to hold the lever in a depressed position. The strap *M* of the central brake is arched to straddle the 20 row, and the chain of this brake passes around a friction-pulley, *O'*, in order that sidewise movements of the central brake may be accomplished as easily as possible. The beams *H* of the central brake are each provided with a 25 stirrup, *H'*, in order that an operator, while sitting in the seat *B*, may with his feet guide the central brake along crooked rows, and thus avoid destroying the crop where the 30 rows are crooked.

30 Each of the side brakes is provided near its pivotal connection with a cross bar or strap, *R*, (see Fig. 5,) which projects outwardly, and is connected by a link, *S*, to a depending bracket, *T*, through which the link is passed, 35 and by means of nuts *U* the link is drawn so as to determine the path of the side brake. In this manner they are prevented from approaching too near the side rows of the crop.

I do not wish to be understood as limiting 40 myself to all of the details or the exact proportion and relative arrangement of the parts herein shown, as I may vary the same in any measure and to any degree within the skill of persons conversant in constructing agricultural 45 implements.

It will be seen that by moving the straps, bands, or bars *M* along the arms *H*, the shovels may be regulated as to their distance apart, so as to adapt them to rows of different width.

50 When the corn or other plants have grown too tall to use the central brake, the latter may

be disconnected from the frame, and be either dispensed with or secured to and made to drag in the rear of one of the side brakes.

Having described the construction and operation of my invention, what I claim as new, and desire to secure by Letters Patent, is—

1. In a cultivator of the class described, the three pairs of shovels, each pair constructed as shown, and pivoted to the frame independently of the others, substantially as specified. 55

2. In a cultivator of the class described, the three separate pairs of shovels independently and pivotally connected to the frame, substantially as specified. 60

3. In a cultivator of the class described, the combination, with the frame, of two independent outside brakes, each carrying a pair of shovels, and a central independent pivotally-connected brake carrying a pair of shovels, 70 substantially as specified.

4. In a cultivator, the combination of a brake comprising two beams and a uniting band or strap, a bracket with a sliding clevis, provided with a link horizontally pivoted thereto and vertically pivoted to said beams, substantially as specified. 75

5. The combination of the beams *H* *H*, link *L*, having vertical pivots *h* and horizontal pivots *l*, and the clevis *K*, substantially as shown 80 and described.

6. The combination of the brakes *F* *F*, the central brake, *E*, links *L*, clevises *K*, brackets *J*, chains *N*, shaft *O*, pulley *O'*, and lever *P*, substantially as shown and described. 85

7. The combination of the side brakes, *F*, straps *R*, links *S*, and bracket *T*, substantially as shown and described.

8. The combination of the central pivotally-connected brake, *E*, provided with stirrups *H'*, 90 with the independent side brakes, *F*, on each side thereof, provided with the chain *N*, strap *R*, and with the link *S* and means for adjusting the same as to its length, substantially as shown and described. 95

In testimony whereof I affix my signature in presence of two witnesses.

WILLARD M. HARRIS.
